(57) **CLAIM**

The ornamental design for a component of a construction set, as shown and described.

DESCRIPTION

FIG. 1 is a top front perspective view of a component of a construction set showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The solid lines along smooth transitions between surfaces (e.g., at tangential transitions between curved and flat surfaces or between smoothly connecting curved surfaces) show contour and not surface ornamentation.

The dashed broken lines in the figures show portions of the component of a construction set that form no part of the claimed design.

The dot-dash broken lines in the figures show boundaries that form no part of the claimed design.

The component of a construction set is shown with a symbolic break in its length. The appearance of any portion of the article between the break lines forms no part of the claimed design.
